UNITED STATES PATENT OFFICE.

ROBERT WINES, OF JEFFERSON CITY, MISSOURI, ASSIGNOR TO THE J. S. SULLIVAN SADDLE TREE COMPANY, OF SAME PLACE.

SADDLE-TREE FORK.

SPECIFICATION forming part of Letters Patent No. 357,297, dated February 8, 1887.

Application filed August 19, 1886. Serial No. 211,306. (No model.)

To all whom it may concern:

Be it known that I, ROBERT WINES, of Jefferson City, Missouri, have made a new and useful Improvement in Saddle-Tree Forks, of which the following is a full, clear, and exact description.

In the present fork the pommel is hollow or closed, or substantially closed, at its upper end, and provided with a flange which extends 10 around the pommel-top, forming a recess, into which a wooden cap is set and secured by means of screws passing upward through the pommel-top into the cap.

The fork is used in combination with a detachable breast, and for the purpose of securing it to the breast the fork has an extension leading directly forward over and toward the front of the breast, and also an extension at each side leading downward toward the lower 20 end of the breast, all substantially as is represented in the annexed drawings, making part of this specification, in which—

Figure 1 is a front elevation of the improved fork and breast. Fig. 2 is a plan, the cap being removed. Fig. 3 is a vertical section on the line 3 3 of Fig. 2. Fig. 4 is a vertical section on the line 4 4 of Fig. 2, the cap being in place upon the pommel-top. Fig. 5 is a vertical section on the line 5 5 of Fig. 1; and Fig. 30 6 is a view in perspective of the improved fork and breast.

The same letters of reference denote the same parts.

A represents the fork having the side extensions, $a a$, the extension a' , the pommel a'' , made hollow, saving at its top, where it is

closed, or substantially closed, and preferably by means of the thin head a'' , at the periphery of which is the upwardly-projecting flange a' , which extends all around the pommel-top, 40 forming the recess to receive the wooden cap B, which is secured in the recess by means of the screws $b b$, Fig. 4.

The fork is secured to the breast C by means of the fastenings c , which pass through the extensions $a a$ into the breast, which, in turn, is adapted to be secured to the customary tree, and by being detachable, as described, a longer or shorter breast can be used, as desired.

As is well understood, the pommel of saddles of the kind under consideration are subjected to strains mainly from a direction in front of the pommel. It is desirable, therefore, to brace the pommel well in front, as by means of the extension a' , which extends from the base of the pommel directly forward upon the highest part of the breast, and in the place of being made of uniform width throughout its length, the extension a' is preferably wider at the pommel, from which point it tapers, as shown.

I claim—

The combination of the fork and the detachable breast, said fork having an extension leading directly forward over and toward the front of the breast, and also side extensions, substantially as described.

ROBERT WINES.
